HINGE

Filed July 15, 1929

UNITED STATES PATENT OFFICE

CLIFTON E. THOMPSON, OF GRAND RAPIDS, MICHIGAN

HINGE

Application filed July 15, 1929. Serial No. 378,239.

The main objects of this invention are:

First, to provide a hinge which is well adapted for water closet seats and covers having substantially no exposed part when the cover is closed.

Second, to provide a hinge which enables the assemblage of the supported parts without the aid of tools.

Third, to provide a structure in which the hinge members may be readily attached to the parts which they are to support.

Fourth, to provide a structure having these advantages which is very economical and at the same time strong and durable and attractive.

Objects relating to details and economies of my invention will appear from the description to follow. The invention is defined and pointed out in the claim.

A structure which is a preferred embodiment of my invention is illustrated in the accompanying drawings, in which:

Fig. 1 is a plan view of a toilet seat embodying the features of my invention, a portion of the cover being broken away to show structural details.

Fig. 2 is a fragmentary rear elevation with the cover lifted.

Fig. 3 is a fragmentary view partially in section on line 3—3 of Figs. 1 and 2.

Fig. 4 is a fragmentary view partially in section on line 4—4 of Fig. 2 showing the seat in lifted position, the cover being omitted.

Fig. 5 is a fragmentary sectional view of the part shown in Fig. 4 with the seat swung to a position for engagement and disengagement with the post.

Fig. 6 is a rear perspective view of the post.

In the accompanying drawings, 1 represents the bowl, 2 the seat and 3 the cover of a water closet.

On the bowl I mount a pair of posts 4, the supporting bolts being shown at 5. These posts are provided with spaced ears or knuckles 6 having curved peripheries and carrying the pintle 7, this pintle projecting at each side of the knuckles. The knuckles are notched or recessed at 8, the purpose of which will appear later.

The seat is provided with notches or recesses 9 in its rear edge adapted to receive the U-shaped hinge members 10, these hinge members fitting within the recesses 9 and being secured therein by screws 11 in the embodiment illustrated. However, where the seats are molded or formed of composition, the composition may be molded upon these hinge members.

The arms 12 of the hinge members 10 are provided with outwardly and rearwardly inclined slots 13 open at their ends. The arms also have flange-like parts 14 projecting from their inner edges to overlie and engage the peripheries of the post or support knuckles, thereby retaining the hinge members in engagement with the pintle until the seat is swung to a rearward position, as shown in Fig. 4, in which position the ends of the retaining flanges 14 lie within the notches or recesses 15, consequently permitting the engagement and disengagement of the hinge member with the pintle of the post. However, throughout the swinging movement of the seat, the parts 14 overlap the knuckles thereby preventing the disengagement, as stated.

The cover 3 is provided with a hinge member 16 having a screw 17 threaded into the underside of the seat. This hinge member is provided with a knuckle 18 having a slot 19 therein engageable with the pintle between the knuckle members of the post or support, the periphery of the knuckle 18 engaging the post between its knuckles, as shown in Fig. 3, thereby retaining the hinge member 16 in pivotal engagement with the bolt 7 until the hinge member 16 is swung to an approximately reversed position which permits the engagement and disengagement of the hinge member with the pintle. However, throughout the range of the scope of swinging the cover, the parts are retained very effectively in engagement.

While my improved hinge is especially designed by me for water closet seats and covers, it is readily adapted and desirable for use in other relations. It is particularly desirable for use on water closet seats in that the hinge members are secured to the cover and seats.

without the use of exposed bolts or screws. While the swinging members of the hinge may be quickly engaged and disengaged on the supporting member, in ordinary installations it is not possible to disengage the same without disassembling from the bowl; that is, it is not possible to swing the cover and the seat rearwardly far enough to permit engagement and disengagement.

10 I have illustrated and described my improvements in an embodiment which I have found very practical. I have not attempted to illustrate or describe certain modifications and adaptations as it is believed that this disclosure will enable those skilled in the art to embody or adapt my improvements as may be desired.

Having thus described my invention, what I claim as new and desire to secure by Letters 20 Patent is:

In a structure of the class described, the combination of a post provided with a knuckle and with a pintle projecting at each side thereof, and a U-shaped hinge member 25 having outwardly inclined slots in its arms coacting with the ends of said pintle and having a flange-like knuckle engaging portion on the outer edge of one of its arms coacting with the periphery of the knuckle, said 30 knuckle being notched at the base thereof to permit engagement and disengagement of the hinge member when its said knuckle engaging portion is swung into said notch.

In witness whereof I have hereunto set my 35 hand.

CLIFTON E. THOMPSON.
